UNITED STATES PATENT OFFICE.

CHARLES AUGUSTUS STRAUB, OF ROUSEVILLE, PENNSYLVANIA.

BOILER-PUMP REGULATOR

SPECIFICATION forming part of Letters Patent No. 555,540, dated March 3, 1896.

Application filed June 15, 1895. Serial No. 552,940. (No model.)

To all whom it may concern:

Be it known that I, CHARLES AUGUSTUS STRAUB, a citizen of the United States, residing at Rouseville, in the county of Venango and State of Pennsylvania, have invented a new and useful Boiler-Pump Regulator, of which the following is a specification.

This invention relates to an improvement in feed-regulating devices for steam-boilers, and has for its object to provide a feed-regulator of simple, inexpensive, and efficient construction, which will operate automatically to throw the injector-pump into and out of operation for the purpose of maintaining the water at the desired level in the boiler.

A further object of the invention is to provide, in connection with such regulator, means whereby the water may be maintained at different levels in the boiler and the steam-pressure varied to suit the conditions required.

In order to accomplish the objects above mentioned, the invention consists in an improved mechanism for automatically regulating the feed of water to steam-boilers, embodying certain novel features and details of construction and arrangement of parts, whereby advantages in point of simplicity and efficiency are attained, as hereinafter fully described, illustrated in the drawings, and finally embodied in the claims.

In the accompanying drawings, Figure 1 is a view in elevation of the improved boiler-feed regulator, showing the relation thereof to the injector-pump and the steam and water pipes, valves, &c. Fig. 2 is a vertical sectional view through the improved regulator and the steam-cut-off valve through which the steam is admitted to the pump.

Similar numerals of reference designate corresponding parts in both figures of the drawings.

Referring to the accompanying drawings, the regulator contemplated in this invention comprises an upper disk, 1, and a lower disk or head, 2. These disks or heads are formed with circular recesses in their adjacent faces, as shown, and each has bolted thereto a ring or annular plate 3 of the same diameter and secured to its inner face. Arranged between each disk or head and its ring or annular plate 3 is a circular diaphragm 4, of any suit-

able flexible material, and which will hereinafter be designated as the "upper" and "lower" diaphragms. The upper and lower heads of the regulator thus far described, together with the rings and diaphragms, are spaced a convenient distance apart, and so held by means of tie bolts or rods 5.

6 designates a metal bracket, the upper portion of which fits between the rings 3 of the upper and lower regulator-heads, the latter being bolted or otherwise secured to said bracket which forms the support for the regulator. This bracket is itself supported by 65 means of a depending portion or arm 7, which extends downwardly to, rests upon, and is suitably connected with the case of the steam-cut-off valve 8.

9 designates a lever, which is pivotally connected with or fulcrumed within an opening in the bracket 6 upon a stationary pin 10.

11 represents a pressure-head, the middle portion of which is slotted or apertured to permit the passage of the lever 9, the same being connected by a pivot 12. The upper and lower ends of this pressure-head are expanded in diameter, as shown, and are adapted, when properly adjusted, to rest in contact with the inner adjacent faces of the upper 80 and lower diaphragms 4. The lever 9 is connected at one end by means of a ball-and-socket joint, or in any convenient manner, with the upper end of the stem 13 of the steam-cut-off valve 8, above referred to, while 85 the opposite end of said lever is provided with a ball or weight 14^a, which is capable of being moved lengthwise of that end of the lever, for a purpose that will be hereinafter set forth.

14 designates the steam-supply pipe, which connects at one end with the steam-space of the boiler and at its opposite end with the steam-chest of the injector-pump, the steam-cut-off valve 8 being arranged at any convenient point between the ends of said pipe. 90 15 indicates a small branch pipe, which communicates with the steam-supply pipe 14 and with the space in the upper head of the regulator above the upper diaphragm. 16 represents the water-supply pipe by which the injector-pump is fed, and 17 the water-pipe which leads from the pump to the boiler. 95 18, leading to different boilers where a gang

The pipe 17 may have two or more branches

is employed, and is connected with the lower head of the regulator by means of a small branch pipe 19, which communicates with the space in said head below the lower diaphragm.

5 The operation of the device will be readily understood with a little additional explanation in view of the description of the regulator and the relative arrangement of its parts and the several pipes connected therewith, 10 as above noted.

The steam-pressure in the boiler being practically constant and uniform, a corresponding pressure will be exerted against the upper diaphragm, while the pressure against the lower diaphragm is variable and changes according 15 to the depth of water in the boiler. When the water is at a predetermined level in the boiler, the steam and water pressures counterbalance each other with relation to the 20 regulator and thus hold the steam-valve closed. When, however, the head or level of the water in the boiler falls, the reduction in the weight of water effects a corresponding decrease in the pressure against the lower diaphragm, and the excess of steam-pressure 25 causes the regulator-head to descend sufficiently to open the steam-valve and admit steam to the pump-engine. The pump is thus thrown into action and continues to work 30 until the proper water-level is again attained in the boiler, whereupon said water will press against the lower diaphragm with a force sufficient to counterbalance the steam-pressure on the upper diaphragm, thus closing the 35 steam-valve and checking the pump. By moving the weight 14 in or out upon the lever 9 the amount of water fed to the boiler may be regulated as desired.

Various changes in the form, proportion, 40 and minor details of construction may be resorted to without departing from the spirit or sacrificing any of the advantages of this invention.

Having thus described the invention, what 45 is claimed as new, and desired to be secured by Letters Patent, is—

1. A feed-regulator for steam-boilers, comprising two flexible diaphragms arranged in such manner as to be acted upon, one by 50 steam-pressure and the other by water-pressure, and a lever interposed between said diaphragms and adapted to be influenced thereby for operating the steam-cut-off valve, for throwing the injector-pump into and out of 55 operation, in the manner substantially as described.

2. A feed-regulating device for steam-boilers, comprising two diaphragms mounted within a suitable frame or case and spaced a 60 suitable distance apart, a lever interposed between said diaphragms and mounted pivotally within said frame, and a pressure-head hinged to said lever and interposed between and having its ends in close proximity to said 65 diaphragms, all arranged for joint operation, substantially as described.

3. A device for regulating the feed of steam

boilers, comprising two diaphragms spaced a suitable distance apart, the regulator-heads or frame-plates in which said diaphragms are 70 mounted, the tie-bolts interposed between and connecting said heads, a valve-operating lever interposed between said diaphragms and heads, and a pressure-head having a pivotal relation to said lever and resting with its opposite ends against or in close proximity to said diaphragm, substantially as specified.

4. A feed-regulating device for steam-boilers, comprising two flexible diaphragms, the regulator-heads in which said diaphragms are 80 mounted constructed to afford steam and water spaces upon the outer opposite faces of said diaphragms and provided with openings for the introduction of steam and water pipes, a pressure-head disposed between said diaphragms and adapted to be operated thereby, 85 and a steam-valve-operating lever mounted upon a stationary pivot and pivotally connected to said pressure-head, said lever being also provided with a movable counterbalance-weight, all arranged for joint operation, substantially as specified.

5. A feed-regulating device for steam-boilers, comprising two diaphragms, the regulator-heads in which said diaphragms are suspended, tie bolts or rods connecting said heads, a bracket having a portion thereof interposed between and bolted or otherwise secured to said heads for supporting the latter, and provided with an arm or support adapted 100 to be connected with the steam-valve or other convenient point of support, a valve-operating lever hinged to said bracket, and a pressure-head disposed between the diaphragms and pivotally connected with said lever, substantially as and for the purpose specified.

6. In a feed-regulating device for steam-boilers, the combination with the injector-pump, the steam-supply pipe leading thereto and the water-pipes leading therefrom to the 110 boiler, of a regulator interposed between said steam and water pipes, said regulator comprising two diaphragms mounted within suitable heads constructed in such manner as to leave steam and water spaces adjacent to said 115 diaphragm, a steam-pipe branch interposed between the steam-supply pipe and one of the regulator-heads, a water branch pipe interposed between the water-pipe proper and the opposite regulator-head, and a lever interposed between said diaphragms and capable of being influenced thereby, said lever being operatively connected with the steam-valve which regulates the flow of steam to the injector-pump, substantially as specified and 120 for the purpose set forth.

In testimony that I claim the foregoing as my own I have hereto affixed my signature in the presence of two witnesses.

CHARLES AUGUSTUS STRAUB.
